MULTIOFFICE TELEPHONE SYSTEM

Fernand P. Gohorel, Antony, France, assignor to
 International Standard Electric Corporation,
 New York, N. Y., a corporation of Delaware

Application October 23, 1943, Serial No. 507,469
 In France December 5, 1938

6 Claims. (Cl. 179—27)

1

The present invention relates to various improvements in telephone systems, and particularly in systems comprising several exchanges connected by cables, and in which communication between subscribers of different exchanges may be established wholly by the operator of the outgoing exchange without the intervention of the incoming operator, or of the operators of the intermediate exchange or exchanges.

One of the characteristics of the invention consists in that the dialling impulses, which are transmitted in the form of interruptions of a dialling current, become effective at the incoming exchange where they are recorded during the interruption of the current, only when the dialling current is re-established.

Another characteristic of the invention consists in that when a dialling impulse which is transmitted in the form of an interruption of a dialling current has been recorded, the recording device can record the next impulse only when the previous impulse has become effective and has thus caused a particular operation or signalling function.

Another characteristic of the invention consists in that the device rendering the impulses effective, operates only if the duration of the interruption of the dialling current does not exceed a predetermined maximum value.

Another characteristic of the invention is that a series relay in the device which renders the impulses effective can operate only if operating impulses are received.

Another characteristic of the invention consists in that the devices on which the impulses must be received can participate in the hunting for the calling line only after a preliminary local test under normal conditions of operation of their detection device and of the impulse relay which is associated with said detection device.

Another characteristic of the invention consists in that the signal indicating that the impulse transmission is at an end is constituted by the stoppage of the transmission of the dialling current from the transmitting station.

Another characteristic of the invention consists in the use at the transmitting station, and at the receiving station, of a single control switch in order to produce the different transmissions of low frequency signalling or supervisory currents.

Another characteristic of the invention consists in that each operator has at her disposal two means of access to the trunks leading to the incoming exchange: The establishment of the connection through a first channel causes the trans-

2

mission from the outgoing exchange of a predetermined signal which effects the necessary switching operations to connect at the incoming exchange, the circuit to a predetermined operator, or subscriber. The establishment of the connection through a second channel does not produce any predetermined operation; this operation can be effected only when the operator works her dial.

10 Another characteristic of the invention consists in that when the operator is connected with a junction circuit over the first channel, a momentary emission of the dialling current without interruptions will send a predetermined signal from 15 the outgoing exchange.

Various other characteristics will appear from the following description given by way of a non-limiting example. In the attached drawings:

Fig. 1 represents a portion of a cord pair of an 20 operator's position necessary for understanding the operation of the device;

Fig. 2 is the outgoing equipment of a circuit 25 between exchanges;

Fig. 3 is the incoming equipment of a circuit between exchanges;

Fig. 4 is an impulse recording device associated 30 with the incoming equipment;

Fig. 5 is a detector or receiving device for transforming the alternating current impulses received 35 into direct current impulses;

Fig. 6 is the equipment of an inter-office trunk leading to the operator's position at the incoming exchange;

Fig. 7 shows a device for establishing a connection 40 between the incoming equipment of an inter-office trunk and the automatic equipment of the incoming exchange; and

Fig. 8 shows the manner in which Figs. 1 to 7 should be connected.

40 In the following description the relay contacts which are closed when the relay is energized, that is to say in operative position, are indicated by placing ahead of the number of the spring the letter T, and the contacts which are closed when

45 the relay is not energized, that is to say, in normal position the letter R. The contacts of the control switches are represented by the shaded squares inserted in the circuits. At each square the positions of the wipers in which the control 50 switch closes the contact are designated, as is the wiper of the control switch which closes the contact.

The operation of the system will be explained in detail in the case in which the operator of the 55 outgoing exchange calls a subscriber connected to

the automatic switchboard of the incoming exchange.

The operator of the outgoing exchange plugs the cord pair of Fig. 1 into the jack J of the equipment of Fig. 2.

Relay 4 is energized through its lower winding in the circuit: earth, lower winding of 4, R51, jack J, sleeve of plug C, windings in series of relay 1 and battery. On account of the high resistance of relay 4, relay 1 cannot attract its armature. Relay 4 closes at T42 the starting circuit of cams C1 and C2. At T41, it closes the circuit of relay 4' which opens at R41' the circuit of the "disengaged" lamps.

The operator depresses the listening key CE and the dial key CD of the cord pair, Fig. 1. The following circuit of relay 6 is completed: earth, winding of 6, R54, jack J, plug sleeve n of the cord pair, contact key CA in normal position, spring 1 of key CE in operative position, spring 1 of key CD in operative position, resistance R2 and battery. At T63, relay 6 completes the circuit of the windings in series of relay 5 through the windings of relay 1. Relay 5 pulls up, but relay 1 cannot be energized on account of the high resistance of the upper winding of 6. At T62, relay 6 completes the circuit of relay 9 which pulls up. At T52, relay 5 completes the following circuit of relay 7: earth, R41, T52, winding of 7, and battery. At T73, relay 7 completes its holding circuit to earth of R84. At T71, it completes the following stepping circuit of the control switch: earth, cam C2, T71, R101, T67, contact of wiper e of the control switch in position O, stepping magnet Cm of the control switch.

The control switch advances one step and passes to position 1. From that time said control switch makes a complete rotation, the circuit of the magnet CM being closed over cam C2 by wiper e in the positions 1 to 10, and by wiper f in the positions 11 to 21.

When the control switch leaves its normal position O, it opens the line wires L1 and L2 of the equipment of Fig. 2 and connects them through wipers a and b, and in positions 1 to 10 to the low frequency current generator Ge1.

A calling impulse is thus sent over conductors L1—L2 which, at the incoming exchange is received by the relay 18.

Through T181, relay 18 completes the circuit of the lower winding of relay 19 which pulls up, and of the winding of relay 20 which pulls up a little later. The following circuit of the lower winding of relay 22 is completed: earth, T193, T201, R211, lower winding of 22 and battery.

When the relay 22 pulls up, the starting circuit of the registers is completed through T222, and R232 and wire 52'. It will be assumed that the first free register in engagement with the equipment of Fig. 3 is that of Fig. 4.

When earth has been applied to wire 52', it passes in the normal positions of the switches Co1 and Co2, over R325', to energize the lower winding of relay 23 which pulls up. Moreover, this earth passes through wire 22', R471, R504, to energize the lower winding of relay 51 of the equipment of the detector of Fig. 5.

Relay 51 connects at T514 and T516 the voice frequency current generator Ge3 to the input circuit of the detector device Dr so as to test said device. The detector device Dr may be of any type capable of transforming the alternating current impulses received into direct current impulses.

The device Dr thus detects the current from

the generator Ge3 causing the energization of relay 53. Through T531, relay 53 completes the circuit of the upper winding of relay 52 through T511. Relay 52 pulls up and at T511 completes its holding circuit on its lower winding; at R524 and R522, it disconnects the generator Ge3 from the detector Dr whereupon relay 53 falls off.

When relay 53 returns to normal, the following holding circuit for relay 50 is completed: battery, resistance R3, R531, T513, T523, upper winding of 50 and earth. Relay 50 pulls up and at T501 closes its holding circuit to earth applied to wire 24', at T282 by relay 28; at T74, it opens the holding circuit of relay 26 which falls back. At T502, it applies earth to wire 23' thus completing the circuit of the lower winding of relay 30 which pulls up.

The following automatic stepping circuit of the finder switch Co3 associated with the register is completed: earth, R323, R291, T302, contact of magnet Cm3, magnet Cm3 and battery.

The wipers of Co3 advance in search of the incoming equipment (Fig. 3) on which a call has been received.

When the wipers of Co3 arrive on the bank contacts to which the equipment of Fig. 3 is connected, the following circuit is completed: battery, windings of relay 25, wire T, bank contact, wiper T, windings in series of the relay 29, T303, R331, R291, and earth. Relay 29 is energized if no register is connected with the equipment of Fig. 3, and opens at R291 the circuit of magnet Cm3. The wipers of Co3 remain in engagement with the equipment of Fig. 3. Relay 25 also pulls up.

The following circuit of the upper winding of relay 30 is completed: battery, windings of relay 25, wire T, bank contact, wiper T, upper winding of relay 29, upper winding of relay 30, R331, R391 and earth.

The direction of the upper winding of relay 30 is such that its flux is opposed to that of the lower winding. Under these conditions the armature of relay 30 will fall back. The following circuit of relay 32 is completed: battery, winding of 32, R331, T292 and earth. When relay 32 pulls up, the register and the detection equipment are connected to the incoming equipment.

At the end of the reception the call impulse, relay 18 (Fig. 3) falls back. The lower winding of relay 21 no longer short-circuited and this relay pulls up in series with the lower winding of relay 22. The following circuit of relay 24 is completed: earth, T253, winding of relay 24, T245, contact of wiper C of the control switch in position O, resistance and battery. Through T241, relay 24 completes the following circuit of the stepping magnet of the control switch of the equipment of Fig. 3: earth, cam C3, T241, magnet Cm3 and battery.

The control switch will thus advance under the action of the impulses of the cam C3. During the passage of the wipers of the control switch over positions 1 to 7, the following circuit of relay 7 is completed: battery, winding of 17, contact of wiper a of the control switch in positions 1 to 7, T212 and earth. The relay 17 connects through T172 and T171 the generator Ge1 to the line conductor L1 and L2. An alternating current low frequency impulse is thus sent to the outgoing exchange.

When the control switch leaves position O, the circuit of relay 24 is opened in wiper c of the control switch and the relay falls back. The cir-

75

cuit of the control switch is then completed at T213 and wiper c of the control switch.

When the control switch arrives in position 11, the circuit of its magnet Cm3 is opened and the wipers remain in this position.

When the relay 25 pulls up, it completes at T257 and R282 the circuit of magnet Cm4 of the switch Co4.

When the wipers of Co4 arrive on a free equipment for connection with the automatic exchange, such as that of Fig. 3, relay 28 is energized in the circuit: earth, T212 (relay 27 has pulled up on its lower winding through R265 and T257), windings in series of 28, wiper T, wire 53', R635, R682 and battery through the automatic equipment.

The relay 28 in pulling up, opens at R282 the circuit of magnet Cm4. The wipers of Co4 stop on the contacts to which the equipment of Fig. 7 is connected. The circuit of relay 26 is completed through: earth, T257, T282, winding of 26 and battery. Relay 17 releases when wiper a of the control switch passes position 7. Relay 19 releases a moment after the end of the reception of the calling impulse. Relay 12 connects the line conductors L₁ and L₂ over T251 and T259, and the wires a and b towards the register and the detector device.

The following circuit of relay 64 of Fig. 7 is completed: battery, winding of 64, R632, wire 51', T270, T261, T252, upper winding of 10 and earth. Relay 64 through T644 completes the circuit of relay 63 in series with relay 28 which pulls up.

The loop to the automatic switchboard is completed through: conductor 61', T633, T643, R551, resistance, conductor 62'.

The following circuit of relays 65 (Fig. 7) and 49 (Fig. 4) is completed: earth, winding of 65, T645, T637, wire 52', T274, T267, T150, wire I of Co3, T322, R411, winding of relay 40 and battery. On account of the high resistance of the winding of relay 40, relay 65 cannot be energized, but relay 40 pulls up.

The return impulse sent on the line conductors L₁—L₂ from the incoming exchange is received at the outgoing exchange on relay 12 during the displacement of wipers b and d of the control switch from positions 10 to 21.

Relay 12 completes through T121 the circuit of the lower winding of relay 14 which pulls up and connects the line conductors L₁—L₂ to relay 15 which receives the end of the impulse, and through T151 maintains relay 14 attracted on its middle winding.

When relay 14 pulls up, the circuit of relay 13 is completed through T142, T151 and earth. Relay 13 pulls up after a moment. The following circuit of relay 10 is completed: battery, lower winding of the relay 10, R111, T131, T142, T151 and earth. Relay 10 pulls up and opens at R101 the outgoing circuit of position O of the control switch.

At the end of the reception of the impulse, relay 15 releases and opens the circuit of relay 8 which falls back, as does relay 13. Relay 11 is energized in the following circuit in which the relay 10 is maintained: battery, lower winding of 11, T103, T53 and earth. The following circuit of relay 16 is completed: earth, winding of 16, T114, T69, tip of the plug of the cord pair, spring of key CA and its rest contact, spring I of key CE and its work contact, spring 2 of key CD and its work contact, spring Cn of the operator's dial, signal lamp L1, resistance and battery. Relay 16 is energized and lamp L1 lights up, indi-

cating to the operator that she can begin to dial the desired subscriber's number.

Relay 16, which has pulled up, connects the line conductors L₁ and L₂ to the terminals of the voice frequency current generator Ge2. This voice frequency current is received on the equipment of Fig. 3, and transmitted to the equipments of Figs. 4 and 5 over the circuits previously traced, and is finally received in the detector device Dr causing the holding of relay 53. The following circuit of relay 36 (Fig. 4) is completed: earth, winding of 36, wire 25', R511, T531, resistance and battery.

It will be seen that at the outgoing exchange owing to the fact that the dial contacts Cn are inserted in the circuit of relay 16, said relay 16 will release for each interruption of contact Cn, that is to say, for each dialling impulse. The result is that the line conductors L₁—L₂ will be disconnected from the generator Ge2 and the transmission of the voice frequency current to the incoming exchange will be interrupted. Thus, the dialling of the called number will take place in the form of breaks in the voice frequency currents of the generator Ge2.

When, during the sending of impulses, the voice frequency current is no longer received at the incoming exchange, relay 53 (Fig. 5) releases and completes the following circuit of relay 34: battery, resistance R531, R513, wire 26', winding 34, T363 (the slow-acting relay 36 does not release during the reception of one train of impulses), R381 and earth. Relay 34 is energized and at T341 completes its holding circuit. At T342, it completes the circuit of relay 38 which pulls up.

At the end of the interruption of the voice frequency current corresponding to one impulse, relay 53 (Fig. 5) is energized and opens the circuit of relay 34 which falls back. Relay 38 is maintained attracted in the circuit: battery, winding of 6, T382, T322', contact for the magnet Cm1 and earth. After the release of 34, the following circuit of the upper winding of relay 37 is completed: battery, upper winding of 37, R372, T361, T383, R342 and earth. Relay 37 pulls up. Through T371, it completes its holding circuit on its lower winding. Through T372, it completes the following circuit for the energization of magnet Cm1: battery, electromagnet Cm1, T372, T361, T303, R342.

The magnet Cm1 attracts its armature and opens its contact which causes the release of 38 and, consequently, the opening at T383 of the circuit of magnet Cm1 which releases its armature, thus causing the advance of the wipers of Co1 by one step.

At R381, relay 38 short-circuits the lower winding of relay 37 which is thus rendered sufficiently slow not to release during the period of the reception of one train of impulses.

It will be noted that if a fresh interruption of current had caused the retraction of relay 53 before the switch Co1 has ended the advance by one step following the previous interruption, relay 34 would have been unable to energize before the release of 38, its holding circuit being opened at R381. Under these conditions the wipers of Co1 will advance one step for each impulse received at the incoming exchange. The wiper b causes the looping of the condenser preceding that explored by the wiper D for the purpose of causing, should occasion arise, the discharge of the condensers which remain prematurely charged.

When the reception of the train of impulses is finished, relay 37 releases after a moment, and

relay 36 is short-circuited by T531, relay 53 being held attracted by the voice frequency current emitted by the outgoing exchange.

The condenser connected to the bank contact on which the wiped *d* of C_{01} has stopped, will be charged in the circuit: battery, resistance, first armature of the condenser C_6 , for example, wiper *d*, T353, T321, T375, windings in parallel of 39 and earth.

During the reception of the second train of impulses, the same operations which have just been described are repeated, and the wipers of C_{01} are stopped on the second condenser which is charged, and also for the various impulse trains.

We will now explain the re-transmission of the impulses to the equipment of Fig. 7.

When relay 35 pulls up, it completes the following circuit of relay 42: battery, winding of 42, R441, R392, T352, T321', and earth. After a moment, relay 42 completes through T421 the circuit of relay 41 which pulls up after a moment. When the impulse contact C_{e1} is opened by a cam driven by motor M_1 the lower winding of relay 43 removes the short-circuit and said relay is energized in the circuit: battery, windings in series of relay 43, T412, R451, R401, T352, T321' and earth.

Relay 43 will thus attract its armature. Through R431 it opens the short-circuit around its lower winding, and through T431 connects through cam C_{e1} magnet C_{m2} of switch C_{02} to the earth through: T412, R451, R401, T352, T321' and earth. Through T432, relay 43 completes the following impulse circuit: battery, resistance, cam C_{02} , R442, T432, T411, T322, wiper I of C_{02} , wire I, T250, T267, T274, wiper B of C_{02} , bank contact, wire 52', T637, T645, winding of 65 and earth.

It will be seen that every time the impulse springs C_{e2} are closed, relay 65 is energized and at R651 opens the loop to the automatic switch, thus causing the routing of the automatic switch in the well-known manner.

The cam which operates contact C_{e2} is driven by the same driving motor M_1 as cam C_{e1} .

When relay 43 pulls up upon the closing of springs C_{e1} , magnet C_{m2} energizes in the circuit previously traced. When the contacts C_{e1} are again opened the magnet C_{m2} is de-energized and the wipers of switch C_{02} advance one step.

By a suitable arrangement on the shaft of M_1 of the cams operating springs C_{e1} and C_{e2} , it is possible to advance by one step the wipers of C_{02} for each interruption of C_{e2} , that is to say, for each pulling up of relay 65, which thus causes an interruption in the circuit of the automatic switch. This constitutes the re-transmission of an impulse.

The wiper A of C_{02} will thus advance over the bank contacts to which the condensers $C_1, C_2 \dots$ are connected. When the wiper arrives on the previously charged condenser (C_6 , for example), then through the wiper *d*, the condenser C_6 , discharged in relay 45, pulls up.

At R451, relay 45 opens the circuit of magnet C_{m2} . The switch C_{02} is stopped in the corresponding position. Moreover, at R451, relay 45 removes the short-circuit from the relay 44 which pulls up in the circuit: battery, windings of 43, T412, windings of 44, R401, T352, T321' and earth.

Relay 44 pulls up and at R442 opens the impulse circuit of the relay 65. The re-transmission of the impulse series to the automatic switch ends.

At R441, relay 44 opens the circuit of relay 32 which falls back, opening at T421 the circuit of

relay 41, which falls back. Relay 41 completes at R411 the circuit of relay 40 in series with relay 63. Relay 40 opens at R401 the circuit of relays 43, 44 and 45, which fall back. As soon as relay 44 falls back, the circuit of relay 42 is again completed, whereby a fresh series of impulses is re-transmitted by relay 65.

It will be noted that when the re-transmission of one impulse train is finished, the beginning 10 of the re-transmission of the next train is controlled by the holding of relay 40. In the example given, this relay holds until relay 41 falls back, earth being applied to the end of the winding of 65. However, the end of the winding of 65 might be grounded under the control of the 15 automatic switch at any moment, so as to cause the re-transmission of an impulse train only when the operations following the previous one have actually been carried out in said automatic switch.

Should the wipers of the switch C_{02} for any 20 reason whatever come against the wipers of C_{01} (end of dialling, for example), that is to say, if they should arrive at the same moment on the bank contacts connected to the same condenser, then the relay 45 will be energized and remain 25 energized in the circuit: battery, winding of 45, wiper *a* of C_{02} , bank contact of C_{02} , corresponding bank contact of C_{01} , wiper *d*, T353, T321, R375, winding of relay 39 and earth. The holding of 30 relay 45 causes the stopping of the transmission of the impulses to relay 65.

When the operator at the outgoing exchange finishes dialling the desired subscriber's number, she disconnects her dial key CD (Fig. 1). The 35 circuit of relay 16 (Fig. 2) is opened, and this relay falls back. The transmission of the voice frequency current over the line wires ends.

At the incoming exchange the elimination of the voice frequency current has the effect of 40 causing the final release of relay 53 which opens the circuit of relay 36. The relay 36 in falling back disconnects at T364 earth from the test wire, the relay 39 having pulled up in series with 45. Relay 29 falls back, opening the circuit of 45 28 and 32, which falls back. When relay 32 falls back, the following circuit for the restoration of switch C_{01} to normal, is completed: battery, magnet C_{m1} , sectors associated with wiper *j* and wiper *f*, R322', contact of magnet C_{m1} and earth.

50 The switch C_{01} returns to its normal position O.

When 32 is released, the following return-to-normal circuit of the switch C_{02} is completed: battery, winding of C_{m2} , contact of C_{m2} , sectors 55 associated with wiper *b*, and wiper *b*, R321' and earth.

The register and the detection device associated therewith are released.

When, at the outgoing exchange the operator 60 has released the dial key CD, the circuit of relay 6 (Fig. 2) is released. The talking circuit of the operator's set is completed over the conductors L_1 — L_2 . Through R64 and T92, the upper winding of relay 5 is short-circuited, which permits 65 relay 1 to be energized in the circuit previously traced. The circuit of the supervisory lamp of L_2 is closed at T_1 to a rotary switch which causes the lamp to flicker.

At the incoming exchange, when the register 70 is released, the circuit of relay 25 (Fig. 3) is opened. This relay falls back and at T252 removes earth from wire 51' of the equipment of Fig. 7.

The talking circuit is completed over the wires 75 L_1 and L_2 and the equipment of Fig. 3, and the

conductors 51' and 52' of the equipment of Fig. 7.

In the equipment of Fig. 7, when earth is removed from the wire 51', relay 64 falls back.

If the line of the desired subscriber is free, relay 66 is energized through: earth, T634, lower winding of 67, winding of 66, and battery through the automatic switch. The ringing tone is transmitted through T661 and T662 on wires 51 and 52' and, consequently, to the operator of the outgoing exchange.

If the subscriber's line is busy, relay 66 is not energized, and a busy tone is sent to the operator of the outgoing exchange through R661 and R662.

When the desired subscriber removes his receiver, relay 67 is energized and at T671, closes the circuit of relay 68 which is energized after a moment.

The talking circuit is completed in the equipment of Fig. 7 through: conductor 51', R641, T631, condenser T681, conductor 61' of the automatic switch on the one hand, and on the other hand conductor 52', T637, R645, condenser, T684 and conductor 62' of the automatic switch.

Through T683, relay 68 applies battery to wire 54' through T636 and the following circuit of relay 24 is completed: earth, R181, wiper d of the control in position 11, T215, winding of 24, R53, T262, T271, wiper S, bank contact and battery on wire 54'.

At T241, relay 24 completes the stepping circuit of the control switch through cam C3. When the control switch passes to position 12, and in positions 12 to 21, the circuit of magnet Cm3 is completed through T213, wiper d. The control switch thus returns to normal position O.

During the passage of wiper d of the control switch from position 12 to 18, relay 17 is energized by T212. At T172 and T171, it connects the generator G'e1 to the line conductors L1—L2. A low frequency alternating current impulse is sent to the outgoing exchange. This impulse is received in the equipment of the outgoing exchange (Fig. 2) by relay 12, which pulls up and at T121, completes the circuit of the lower winding of relay 14 which is energized. Relay 14 connects the line conductors at T143 and T141 to relay 15 which receives the end of the impulse. Relay 15, through T151 and T142, completes the circuit of relay 13 which pulls up after a moment.

The following circuit of the upper winding of relay 10 is completed: battery, upper winding of 10, T111, T131, T142; T151 and earth. The two windings of 10 are so arranged that their fluxes are opposed. When its upper winding is energized its lower winding already being energized, the relay 10 releases its armature. Relay 11 is maintained attracted on its upper winding through earth at T111 and the circuit previously indicated.

At the end of the reception of the impulse, relay 15 falls back causing the release of relay 11. Relay 10, of which the flux should be reversed, falls back and remains down. At T112, relay 11 opens the circuit of relay 9 which falls back, opening at T92 the short-circuit of the upper winding of relay 5, which causes the release of relay 1 of the cord. The lamp L2 stops flickering and the operator is thus advised that the desired subscriber has replied. She can get in touch with the subscriber, warn him that a communication is about to be established and complete the connection to the calling subscriber by the second plug of her cord in the usual way.

We will now explain how the release is effected

at the end of the conversation. We will first assume that the operator of the outgoing exchange is the first to withdraw her plug.

When the control switch arrives in position O, the following circuit of relay 8 is completed: battery, winding of 8, T12, wiper g of control switch in position O, R52, R151 and earth. Relay 8 in pulling up, opens at R84 the circuit of relay 7 which falls back. The starting circuit of the control switch is completed through cam C1 through: R71, T83, wiper e in position O, magnet Cm.

The control switch advances one step and passes to position 1; the circuit of its magnet is then completed through cam C1 and R71 by wiper e of the control switch in positions 1 to 10, and wiper f in positions 11 to 21.

The control switch will thus perform one complete rotation. During the passage of the wipers a and e, in positions 1 to 10, the line conductors L1 and L2 are connected to the low frequency generator G'e1 and a release impulse is sent to the incoming exchange. The profile of the cam C1 is such that the control switch will be much slower than when it is actuated by cam C2. The result is that the period of the release impulse will be far greater than that of a supervisory impulse so as to insure the release, even if a supervisory impulse were being sent from the incoming exchange to the outside exchange.

When the control switch leaves position O, relay 8 falls back. The control switch returns to normal position O, after having made one complete rotation.

At the incoming exchange, the release impulse is received on the relay 18 (Fig. 3) which at T181, completes the circuit of the lower winding of 19 which pulls up. Relay 19 applies earth at T193 to the upper winding of relay 22. The flux of this winding being opposed to the flux of the lower winding, the armature of relay 22 falls back. At the end of the reception of the release impulse, relays 19 and 21 fall back. Relay 21 opens at T212 the holding circuit of relay 26 which falls back causing the release of the equipment of Fig. 7, or of the call equipment (Fig. 6) of the operator.

Should the desired subscriber be the first to hang up, or should the incoming operator withdraw her plug first, the battery on wiper S or on wire S', is replaced by earth. Relay 24 is energized in the circuit: battery, wiper c of the control switch in position O, T215, winding of 9, R253, T262 and either T271 and earth on wiper S, or R271 and earth on wire S'. Through T241, relay 24 completes the circuit of magnet Cm3 of the control switch. The control switch advances to position 11, and during the passage of the wiper a in the positions 1 to 1, the circuit of relay 17 is closed and the generator G'e1 is connected to the line conductors. A low frequency transmitting current impulse is sent to the outgoing exchange.

When the control switch leaves position O, the circuit of relay 26 is opened. This relay falls back and causes the release of the equipment of Fig. 7, or of Fig. 6.

In the outgoing exchange, the impulse is received by relay 12 (Fig. 2) and causes the pulling up of relays 12, 14, 15 and 13. Relay 12' is energized on its lower winding through R111, T131, T142, T151 and earth.

A final low frequency impulse is sent by the final equipment of the cord pair through: generator G'e1, R115, T102, R68, tip of the plug, spring of CA and its rest contact, spring d of CE and its rest contact, relay 2, spring 1 of CE and its

11

rest contact, spring of CA and its rest contact, sleeve of the plug, R65, T104, R116 and generator Ge₁.

The relay 2 is energized and through T21 completes the circuit of 3, which is energized. The following circuit of the end lamp L is completed: earth, T34, R11, lamp L2 and battery. The lamp L2 is lighted indicating to the operator that the communication is finished.

At the end of the reception of the impulse, relay 11 sticks and at R115 cuts off the current transmission from Ge₁ to the final equipment of the cord pair.

When the operator of the incoming exchange withdraws her plug, a low frequency current is sent to the incoming exchange and causes the release of relays 7 and 8. The control switch returns to normal, as has previously been indicated.

We will now explain how the operator at the outgoing exchange can call the operator at the incoming exchange.

The operator at the outgoing exchange inserts the plug of her cord pair (Fig. 1, in the equipment of Fig. 2). The same operations which were previously indicated follow in order to effect the transmission of a call impulse and the seizure at the incoming exchange of a free register detector equipment, and the transmission of the various supervisory signals.

In this case, however, the operator does not dial but merely lifts her dial key CD as soon as the lamp L1 is lighted. The transmission of the voice frequency current ends.

The voice frequency impulse is received, as has been explained, on relay 53 causing the holding of relay 36. At the end of the reception of the impulse, relay 53 falls back and completes the above travel holding circuit of relay 34 which is energized. At T342, relay 34 completes the circuit of relay 38 which pulls up, and at T382 closes its holding circuit through T322', contact of magnet Cm₁ and earth.

Shortly after relay 34 has pulled up, relay 36 being short-circuited at T343, falls back. Earth is applied to wiper V of switch Co₃ through: earth, R342, T383, R361, R351, wiper V.

In the equipment of Fig. 3, earth on wire V, through T254, short-circuits the upper winding of the relay 27, which falls back. Relays 25, 26, 27 and 28 pull up in the same manner as in the previous case.

When the relay 27 falls back, the line conductors L₁—L₂ are disconnected from the switch Co₄ and are connected through R270 and R274 to the equipment of Fig. 6 of the operator's incoming position.

Relay 26 remains attracted, but relay 28, of which the circuit is opened at T212, falls back, opening at T283 the circuit of relay 25, which falls back and causes the release of the register.

The following circuit of relay 58 (Fig. 6) is completed: battery, winding of 58, R571, wire C', T263, R272 and earth. Relay 58 is energized and completes the circuit of the call lamp L2. Through T582 and T581, relay 58 connects the inter-urban ringing tone generator to the line conductors and thus to the outgoing operator.

When the incoming operator plugs in, the circuit of relay 59 is completed through the equipment of the cord pair. Relay 59, at T592, completes the circuit of relay 57 to earth on wire C' and at R571 opens the circuit of relay 58, which falls back. Battery is applied through T591 to wire S' causing the transmission through the

12

equipment of Fig. 1 of a supervisory answer back impulse in the same manner as has been explained in the previous case when battery had been applied to wiper S of Co₄.

The outgoing operator can now communicate with the incoming operator.

In the case in which, after the outgoing operator's equipment has been put in connection with the incoming operator, the incoming operator by keying causes the transmission of a calling current on the conductors A' and B'. This current causes the pulling up of relay 54 which, at T541, applies earth to wire D', energizing the middle winding of the relay 19 and causing it to pull up. The line conductors L₁ and L₂ are cut off at R192 and R194, and the calling current is not sent to the equipment of the outgoing exchange so as to prevent false operations.

At the end of the conversation the release is effected, as has previously been indicated. Obviously, the above operations have only been given by way of non-limiting examples. Any current frequency may be employed for the signalling or dialling to transform the alternating currents into direct current at any stage of the operations, without departing from the spirit of the present invention defined in the claims.

What is claimed is:

1. In a telephone system, a plurality of exchanges, subscribers' lines terminating at said exchanges, operators at the exchanges, trunks interconnecting said exchanges, automatic switches at some of said exchanges numerically operable to establish connections with lines, an impulse device at the calling exchange operator's position, a source of voice frequency current at the calling exchange, means controlled by the impulse device for producing interruptions in said voice frequency current in accordance with numerical designation of the called line, means responsive to said interruptions for controlling the automatic switches at the called exchange to select the called line, and means at the called exchange for measuring the length of said interruptions, and means for permitting an impulse to become effective only if the length of the interruption produced by the impulse device does not exceed a predetermined value.

2. The telephone system according to claim 1, a source of supervisory current at each exchange, and a single control switch at the calling and called exchanges for controlling the transmission of supervisory and voice frequency currents.

3. In a telephone system, a plurality of exchanges, subscribers' lines terminating at said exchanges, trunks interconnecting said exchanges, operators' positions at each exchange, automatic switches at some of said exchanges adapted to be numerically operated to select a line, means at the calling exchange for establishing a first connection from an operator over one of said trunks towards an operator at the called exchange, and means for establishing a second connection from an operator at the calling exchange over one of said trunks towards the automatic switches at the called exchange.

4. The telephone system according to claim 3, switching means at the called exchange for connecting a predetermined operator with the first connection, and means operable upon the establishment of the first connection for sending a predetermined signal from the calling exchange for operating said switching means.

5. The telephone system according to claim 3, and an impulse device at the operator's position

13

in the calling exchange for controlling the operation of said automatic switches over said second connection.

6. The telephone system according to claim 3, switching means for connecting a predetermined operator at the called exchange with the first connection, an impulse device at the operator's position in the calling exchange, a source of voice frequency current at the calling exchange, means controlled by the impulse device for producing interruptions in said voice frequency current in accordance with the numerical designation of the called line to control over the second connection the operation of said automatic switches at the called exchange, and means for 10 15

14

producing a momentary emission of current from said source upon the establishment of the first connection for operating said switching means.

FERNAND P. GOHOREL.
